UNITED STATES PATENT OFFICE

137,528

DESIGN FOR A CLOCK CASE OR THE LIKE

Anne Swainson, Chicago, Ill., assignor to Montgomery Ward & Co., Incorporated, Chicago, Ill., a corporation of Illinois

Application September 11, 1942, Serial No. 108,184

Term of patent 3½ years

(Cl. D42—7)

To all whom it may concern:

Be it known that I, Anne Swainson, a citizen of the United States, residing at Chicago, in the county of Cook and State of Illinois, have invented a new, original, and ornamental Design for a Clockcase or the Like, of which the following is a specification, reference being had to the accompanying drawing, forming a part thereof.

In the drawing:

The clockcase of my design is substantially transparent throughout.

I claim:

The ornamental design for a clockcase or the like, substantially as shown and described.

ANNE SWAINSON.
